HATCH PLUG

Charles David Bonsall, Chicago, Ill., assignor to
Standard Railway Equipment Manufacturing
Company, a corporation of Delaware

Application February 15, 1940, Serial No. 319,047

13 Claims. (Cl. 105—377)

My invention relates to hatch plugs and particularly to hatch plugs of the kind that are used for closing the hatchways of refrigerator cars. The principal objects of my invention are to 5 devise a plug that will be light, that will have its insulating material adequately protected against ingress of moisture, dirt and other foreign matter, that will be substantially free from the injurious effects of warping, and which is so 10 designed that parts that are subject to wear can be easily and rapidly replaced without removing the refrigerator car from its train. The invention consists principally in making the plug in the form of a hollow metal container filled with 15 insulating material and with provision for securing around its sides nailing strips upon which suitable padding is nailed, the nailing strips being preferably detachably mounted. The invention also consists in the parts and combinations 20 of parts hereinafter described and claimed.

In the accompanying drawings, wherein like reference numerals refer to like parts wherever they occur,

Fig. 1 is a plan view, partly in horizontal section, of a hatch plug embodying my invention,

Fig. 2 is a vertical section through the plug on the line 2—2 in Fig. 1,

Fig. 3 is a vertical section through the plug on the line 3—3 in Fig. 1,

Fig. 4 is an enlarged vertical section through marginal portion of the plug on the line 4—4 in Fig. 1,

Fig. 5 is an enlarged fragmentary horizontal section on the line 5—5 in Fig. 2,

Figs. 6, 7, 8 and 9 are views, similar to Fig. 4, showing four modifications of the invention; and

Fig. 10 is a perspective view of the bottom strap shown in Fig. 9.

In the construction illustrated in Figs. 1 to 5 of the accompanying drawings, the side walls of the hatch plug are made in the form of a hollow rectangular frame A with rounded corners. This edge frame or rim is preferably 45 made of a strip or strips of sheet metal pressed into channel shape with its web portion 1 disposed vertically and with outturned flanges 2 and 3, respectively, at the top and bottom thereof. The bottom of the plug comprises a metal plate B whose margins overlap and are secured flatwise, preferably by an edge weld 4 to the lower outturned flange 3 of the metal channel member that constitutes the side frame A. The body portion of the metal bottom plate B has hollow 55 depending ribs 5 pressed therein that extend from

one side to the opposite side of the side frame A and serve to stiffen and strengthen said plate.

The chamber C enclosed by the bottom plate B and edge frame A of the hatch plug is filled with any suitable insulating material 6, such as, for instance, as loosely packed or felted hair or vegetable fibers. A metal top or cover plate D, preferably stiffened or strengthened by hollow upstanding ribs 7 therein, as in the case of the bottom plate B, bears flatwise against the top 10 flange 2 of the side frame A and is fastened thereto, preferably by an edge weld 8. The insulating material 6 is thus sealed hermetically inside the metal shell formed by the edge frame A and the top and bottom closure plates of the 15 plug and consequently is protected against the leakage of water or other liquids and against the ingress of dirt and other foreign matter into the insulation chamber C.

The metal body of the plug is smaller than 20 the hatch opening for which it is designed, and its width and length are increased to fit said opening by means of a wooden filler strip E mounted between the upper and lower flanges of the side frame A to which is tacked suitable 25 padding F. As shown in the drawings, the filler strips E, the top and bottom flanges 2 and 3 of the edge frame A and the top and bottom closure plate D and B are all disposed with their outer edges in flush alinement. The filler 30 strips E are secured by means of through bolts 9 that extend downwardly through said filler strip and the top and bottom marginal portions of the metal body; that is, through registering 35 openings provided therefor in the marginal portion of the top D, the upper flange 2 of the side frame A, said filler strip, the lower flange 3 of said side frame and the margin of the bottom B, said bolts having nuts 10 screwthreaded on their lower ends. As shown in the drawings, the 40 filler strip E is made up of endwise abutting side and corner sections or blocks 11 and 12, respectively. Thus, the filler strip sections are easily 45 separately removable from the metal body of the plug by removing the securing bolts 9 therefor.

The filler strip E serves as a nailing strip for the padding F. This padding comprises a strip or strips 13 of waterproof canvas through whose lower margin brads or small barbed galvanized roofing nails 14 or like fasteners are driven into the lower portion of the filler blocks. Curled hair or other suitable packing material 50 15 is filled in between the canvas strip 13 and the face of the filler strip E and then the upper 55

margin of the canvas strip is secured to the upper portion of said filler or nailing strip by fasteners similar to fasteners 14 for the lower margin of said canvas strip.

5 The hatch plug construction hereinbefore described has numerous advantages. In the first place, it is considerably lighter than the wooden plugs commonly used. Its entire body portion, including the insulation, is permanently assembled, 10 while those parts that are especially subject to wear and injury are easily replaceable without disturbing the body of the plug. Such repairs and replacements are so simple that they may be made while the car is at a regular icing station and without requiring the removal of the car from its train and with little or no delay of the train. As the top of the plug is welded to the sides, the insulating material is kept dry and uncontaminated and a lighter gage of metal 15 may be used in the construction of the plug. Another advantage is that the wooden filler blocks afford great protection against injury by being struck by blocks of ice or other rough usage and thus said filler blocks make it practicable to use lighter gage metal than would otherwise be feasible. While the filler blocks are liable to take up moisture and warp, such warping does not affect the metal frame and is inconsequential because the filler block is not intended to contact with the wall and hatch opening. 20

The construction illustrated in Fig. 6, is similar to that of Fig. 3 except that the through bolt 9a, which holds the wooden filler strip E' in place, is disposed horizontally instead of vertically. In the construction of Fig. 6, the through bolt 9a extends through a hole in the web 1a of a relatively shallow channel in the side frame A' and is preferably welded thereto, as at 16, with 25 its head on the inside of the frame. The filler strip E' has a recess 17 in its outer face to receive the nut 10a that works on the threaded end of the through bolt. In this construction, the padding F is secured as hereinbefore described; 30 but, as it covers the through bolt, the padding must be loosened from the through bolt before the wooden filler can be removed from the metal frame. In this modification, the filler strip E' extends outwardly beyond the margins of the 35 metal frame and thus affords better protection for said frame; and the inner margins of said strip are rabbeted, as at 18, along the top and bottom thereof to bring the outer margins of said strip flush with the outer horizontal faces of the top 40 and bottom closure plates D' and B'. In this modification, the ribs 5a of the bottom plate B' and the ribs 1a of the top plate D' are pressed inwardly instead of outwardly and thus serve as battens to compress the insulation 6 in the 45 closed chamber C formed by said plates and the edge frame A'.

The construction illustrated in Fig. 7 is similar to that shown in Fig. 6, except that the cover plates B' and D', the edge frame A' and the filler strip E' are all removably secured together by screws 19 that pass through vertical holes in said plates and the flanges of said edge frame and are threaded into said filler strip. 50

70 In the construction illustrated in Fig. 8, the body of the plug comprises two main members, namely, a pan-shaped bottom member G and a corrugated top like that shown in Fig. 3. The bottom member G, however, has the side walls formed integral therewith instead of being formed separately as in Figs. 4, 6 and 7. In the con-

struction of Fig. 8, the bottom is pressed up from a sheet of metal with upwardly flaring side walls 20 and with horizontal marginal flanges 21 at the top thereof. The cover D is secured flatwise to the marginal flanges 21 of the bottom member 5 preferably by a continuous edge weld 8a. The chamber between said bottom member and the top is filled with insulation material as in the other constructions. In the construction of Fig. 8, there is a sectional wooden filler strip E2 around 10 the sides of the metal frame and this strip is held by means of through bolts 9b that extend downwardly through the margins of the top member and the marginal flanges of the bottom member and said filler strip, which is held by a nut 10b 15 threaded onto the lower end of said bolt. The padding F is mounted on the outer face of the filler strip as in the other constructions.

The construction illustrated in Figs. 9 and 10 is similar in all respects to that shown in Fig. 8, 20 except only that metal straps or strips 22 are welded to the bottom of the metal body G and extend outwardly underneath the filler blocks E2 with the through bolts 9b extending through them and with the bolt nuts 10b underneath said 25 straps. Thus the straps serve to more firmly hold the filler blocks in place.

Reference is hereby made to my copending application Serial No. 327,825, filed April 4, 1940, 30 for subject matter divided out of the present application.

What I claim is:

1. A hatch plug with metal sides, bottom and top, said sides having a rim portion of the metal 35 extending outwardly therebeyond, strips secured in the angles formed by said sides and the rim portion thereof, and sealing pads secured to said strips.

2. A hatch plug with metal sides, bottom and top, said sides having outwardly flanged portions, 40 nailing strips in the angles formed between said sides and said outwardly flanged portions and detachably secured to said flanged portions, and sealing pads secured to said nailing strips.

3. A hatch plug comprising a metal side frame 45 with outstanding flanges along the top and bottom thereof, top and bottom cover plates secured to the respective top and bottom flanges of said side frame, nailing strips detachably secured to said frame between said top and bottom flanges, 50 and sealing pads secured to said nailing strips.

4. A hatch plug comprising a metal side frame with outstanding top and bottom flanges, top and bottom closure plates for said frame, nailing strips mounted on said frame between the top and bottom flanges thereof, sealing pads secured to said nailing strips, and means for removably securing said nailing strips to said frame. 55

5. A hatch plug comprising a metal side frame with outstanding top and bottom flanges, top and bottom closure plates for said frame, nailing strips mounted on said frame between the top and bottom flanges thereof, sealing pads secured to said nailing strips, and means for removably securing said nailing strips to said frame, said securing means comprising bolts extending through said top and bottom flanges, said cover plates and said nailing strips. 60

6. A hatch plug comprising a metal side frame 70 with outstanding top and bottom flanges, top and bottom closure plates for said frame, nailing strips mounted on said frame between the top and bottom flanges thereof, sealing pads secured to said nailing strips, and means for removably securing said nailing strips to said frame, said 75

securing means comprising screws extending downwardly through said top cover plate and said top flanges into said nailng strips and screws extending upwardly through said bottom cover plate and said bottom flanges into said nailng strips.

5 7. A hatch plug comprising a metal side frame with outstanding top and bottom flanges, top and bottom closure plates for said frame, 10 nailng strips mounted on said frame between the top and bottom flanges thereof, sealing pads secured to said nailng strips, and means for removably securing said nailng strip to said frame, said securing means comprising bolts extending 15 horizontally through said side frame between the top and bottom flanges thereof and through said nailng strips.

8. A hatch plug comprising a metal side frame and metal top and bottom closure plates therefor, 20 said frame having an outwardly opening channel extending around the outer side face thereof, a nailng strip removably mounted in said channel, said nailng strip comprising side and corner sections, and a sealing pad secured to the outer 25 face of said nailng strip.

9. A hatch plug comprising a metal side frame with walls of channel-shaped section with its flanges turned outwardly at top and bottom thereof, a bottom secured to said metal frame, a 30 top secured to said metal frame, nailng blocks mounted in the side frame channels and removable therefrom without disturbing the top or bottom, and sealing pads secured at top and bottom to said nailng blocks.

10. A hatch plug comprising a metal side frame with walls of channel-shaped section with its flanges turned outwardly at top and bottom thereof, a corrugated metal bottom secured to said metal frame, a corrugated metal top secured 5 to said metal frame, wooden nailng blocks mounted in the side frame channels and removable therefrom without disturbing the top or bottom, and sealing pads secured at top and bottom to said nailng blocks.

10 11. A hatch plug comprising sides, bottom and top constituting a hollow chamber and insulating material in said chamber, said side walls having an outwardly opening horizontal channel, nailng strips detachably mounted in said channel and 15 padding secured to the outer faces of said nailng strips.

12. A hatch plug comprising sides, bottom and top constituting a hollow chamber and insulating material in said chamber, said sides consisting of 20 channel-shaped metal with its flanges turned outwardly at top and bottom thereof, wooden blocks mounted in the side channels, and padding secured to said wooden blocks.

13. A hatch plug comprising a metal edge frame 25 with outwardly extending top and bottom flanges and top and bottom cover plates permanently secured flatwise to the respective top and bottom flanges, a nailng strip detachably mounted in said edge frame between the top and bottom 30 flanges thereof, and padding secured to the outer face of said nailng strip.

CHARLES DAVID BONSALL.
